FABRIC TESTER

Harold A. Seyboth, Coronado, Calif.

Application March 3, 1948, Serial No. 12,841

9 Claims. (Cl. 73—102)

(Granted under the act of March 3, 1883, as
amended April 30, 1928; 370 O. G. 757)

1

This invention relates to a fabric tester, and more particularly to a fabric tester for evaluating the strength and integrity of fabric covered aircraft surfaces.

Various devices have been developed in the past in an attempt to evaluate the condition of installed aircraft fabrics. None of these attempts has proved to be satisfactory. Furthermore, none of these devices provides direct, rapid and accurate evaluation of installed fabric surfaces except by methods involving extensive destructive tests and requiring experienced personnel.

Therefore, an object of this invention is to provide a fabric tester which will permit direct, rapid, and accurate evaluation of the condition of installed fabric surfaces.

Another object of this invention is to provide a fabric tester which imposes a minimum of damage to the parts or surfaces under test.

Another object of this invention is to provide a fabric tester which will permit accurate evaluation of the condition of doped fabric surfaces, irrespective of the condition of the dope film.

Another object of this invention is to provide a fabric tester which does not require trained personnel for its operation, nor independent judgment on the part of personnel operating the tester.

A further object of this invention is to provide a fabric tester which is portable and inexpensive and can be used directly on the fabric surface of a plane.

A still further object of this invention is to provide a fabric tester which during use imposes damage to fabric so small in extent that it is possible to repair the damage on the spot, while still conforming to aeronautical codes of safety.

Other objects and many of the attendant advantages of this invention will be readily appreciated as the same becomes better understood by reference to the following detailed description when considered in connection with the accompanying drawings wherein:

Fig. 1 is a view of the instant tester broken away to show its component parts, and in engagement with the fabric.

Fig. 2 is a view taken on line 2—2 of Fig. 1 with the fabric omitted.

Fig. 3 is a somewhat diagrammatic view to illustrate the inter-relation of significant dimensions.

Referring to Fig. 1 of the drawing, the numeral 10 identifies a cylindrical casing having a circular flange 11 on one end, adapted, when the tester is in use, to abut at its leading edge 12, a sheet of taut fabric 13, stretched over the frame of an airplane, two ribs 14 of which are shown.

2

A cylindrical plunger 15, slidably mounted in the casing 10, extends beyond the flange 11 and terminates in a fabric-penetrating, circular concave point 16. The length "L" of the point 16, from its apex 17 to its base 18, is preferably made greater than the diameter "D" at its base 18. It is further preferred to limit the length L to a value between D and 2D. The radius "R" of the concavity 19 of the point 16 is preferably greater than 1.25 times the diameter D and less than 6 times the diameter. The diameter "D'" of the flange 11 is preferably greater than two times the diameter D and less than 4 times D.

Means is provided for biasing the point 16 outwardly of the casing. In this embodiment the means is a spring 21, positioned in the casing 10 circumjacent the plunger 15 and compressed between a shoulder 22 on the plunger 15 and the cap 23 of the casing 10. The shoulder 22, also limits outward movement of the point 16.

The opposite end 24 of the plunger 15 extends through the casing cap 23 and terminates flush with the outer surface of the cap 23 when the tester is not being applied. This end 24 is scaled, in this embodiment, with colored bands 25, to indicate the degree of penetrating resistance of the fabric 13 to the point 16, as shown in Fig. 1. The outer band indicates fabric in a dangerous condition, while the inner bands indicate progressively stronger conditions of the fabric.

Operation

The fabric tester is operated as follows:

The casing 10 is gripped by the operator who pierces the fabric 13 with the apex 17 of the point 16. The tester is then pressed toward and into the fabric, with the axis of the tester being maintained perpendicular to the plane of the fabric, until the leading edge 12 of the flange 11 abuts the surface of the fabric 13, as shown in Fig. 1. The tester is preferably given a slight twist to break any loose threads of the fabric which may be binding the point or any frictional binding of the tester itself which may affect the reading.

The resistance pressure on the point 16 exerted by the fabric compresses the spring 21, permitting the end 24 of the plunger 15 to protrude beyond the cap 23 of the casing, thereby giving an instantaneous and direct reading of the fabric condition, as indicated by the color band which registers with the outer surface of the cap 23.

It has been found in operation that inexperienced personnel can, by the use of the instant invention, quickly and accurately determine the strength of installed aircraft fabric, irrespective of the condition of the dope film commonly coat-

ing such fabrics, and with a minimum of damage to such fabric surfaces.

Obviously, many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. A fabric tester comprising a casing adapted to abut a sheet of taut fabric, a cylindrical plunger slidably mounted in said casing, an end thereof extending beyond said casing and terminating in a fabric-penetrating, circular concave point, said point being movable inwardly of said casing upon pressing of the tester against the fabric, means biasing said point outwardly of said casing, and scale means to indicate the position of said plunger in said casing.

2. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the length of said point being greater than the diameter thereof at its base, the concavity of said point being of radius greater than 1.25 times said base diameter and less than 6 times said diameter, means biasing said point outwardly of said casing, and scale means to indicate the position of said plunger in said casing.

3. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the length of said point being greater than the diameter thereof at its base and less than twice said diameter, means biasing said point outwardly of said casing, and scale means to indicate the position of said plunger in said casing.

4. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the length of said point being greater than the diameter thereof at its base, the diameter of said flange being greater than two times said point diameter and less than four times said point diameter, means biasing said point outwardly of said casing, and scale means to indicate the position of said plunger in said casing.

5. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the

length of said point being greater than the diameter thereof at its base and less than twice said diameter, the concavity of said point being of radius greater than 1.25 times said base diameter and less than 6 times said diameter, the diameter of said flange being greater than two times said point diameter and less than four times said point diameter, spring means biasing said point outwardly of said casing and compressible by said plunger to balance resistance pressure of the fabric against said point, and scale means to indicate the position of said plunger in said casing.

6. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the opposite end of said plunger, in normal inoperative condition, terminating flush with said casing and being scaled to indicate degree of penetrating resistance of the fabric, a spring in said casing, circumjacent said plunger, biasing said point outwardly of said casing and compressible by said plunger to balance resistance pressure of the fabric against said point.

7. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the length of said point being greater than the diameter thereof at its base, the opposite end of said plunger, in normal inoperative condition, terminating flush with said casing and being scaled to indicate degree of penetrating resistance of the fabric, and a spring in said casing, circumjacent said plunger, biasing said point outwardly of said casing and compressible by said plunger to balance resistance pressure of the fabric against said point.

8. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon pressing of the tester against the fabric, the length of said point being greater than the diameter thereof at its base and less than twice said diameter, the diameter of said flange being greater than two times said point diameter and less than four times said point diameter, the opposite end of said plunger, in normal inoperative condition, terminating flush with said casing and being scaled to indicate degree of penetrating resistance of the fabric, and a spring in said casing, circumjacent said plunger, biasing said point outwardly of said casing and compressible by said plunger to balance resistance pressure of the fabric against said point.

9. A fabric tester comprising a casing having a circular flange on an end thereof adapted to abut a sheet of taut fabric, a cylindrical plunger slidably mounted in said casing, an end thereof extending beyond said flange and terminating in a fabric-penetrating, circular concave point, said point being movable inwardly of said casing upon

pressing of the tester against the fabric, the length of said point being greater than the diameter thereof at its base and less than twice said diameter, the concavity of said point being of radius greater than 1.25 times said base diameter and less than 6 times said diameter, the diameter of said flange being greater than two times said point diameter and less than four times said point diameter, the opposite end of said plunger, in normal inoperative condition, terminating flush with said casing and being scaled to indicate degree of penetrating resistance of the fabric, and a spring in said casing, circumjacent said plunger, biasing said point outwardly of said casing and compressible by said plunger to balance resistance of pressure of the fabric against said point. 15
